Letters Patent No. 2383, Dated Aug. 14, 1866.

Design for Coffin Ornamenting

The seeds referred to in these letters Patent and making part of the same.

To all whom it may concern:

Be it known that S. D. Arnold of New Britain
Hartford County and State of Connecticut, have invented a new and
improved Design for Coffin Ornamenting, and do hereby declare
that the following is a full, clear, and exact description thereof which
will enable others skilled in the art to make and use the same
reference being had to the accompanying drawing forming part of this spe-
cification.

The present invention relates to a new and improved Design for ornamenting
to be used upon coffins, burial cases, or caskets and other similar receptacles
for the burying of the dead, and is particularly confined in an
ornamental plate to be attached to the coffin or other case about the
heads of the screws employed for fastening its top to its body portion.

In the accompanying plate my new Design is illustrated, the
Figure being a photographic view of the same.

It represents the plate having through its centre an aperture B, to receive
the fastening screw about the head of which it is to be placed on the coffin or
other burial case. Upon each side of the aperture B, is a rose C, the
stems D, of which, cross each other at the under side or edge of said aperture.
Above the roses C, are rose buds E, with their stems F, crossing each other
at the upper side of the aperture B, the two ends of the plate being formed
of a rose leaf G.

I claim as new and desire to secure by Letters Patent,
The Design herein described and shown in the accompanying plate of illustration
